UNITED STATES PATENT OFFICE.

JOSEPH C. WILLIAMS, OF ETNA, PENNSYLVANIA.

GAS-BURNING PUDDLING-FURNACE.

SPECIFICATION forming part of Letters Patent No. 289,201, dated November 27, 1883.

Application filed September 11, 1883. (No model.)

To all whom it may concern:

Be it known that I, JOSEPH C. WILLIAMS, a citizen of the United States, and a resident of Etna, in the county of Allegheny and State 5 of Pennsylvania, have invented certain new and useful Improvements in Gas-Burning Puddling-Furnaces; and I do hereby declare that the following is a full, clear, and exact description of the invention, which will enable 10 others skilled in the art to which it appertains to make and use the same, reference being had to the accompanying drawings, which form a part of this specification, and in which—

Figure 1 is a perspective view of my improved gas-burning puddling-furnace, showing a part of the casing broken away. Fig. 2 is a side view of the same, showing the side of the casing broken away. Fig. 3 is a longitudinal vertical sectional view on line *xx*, Fig. 1; and Fig. 4 is a vertical sectional view on line *yy*, Fig. 2, looking in the direction of the arrow.

Similar letters of reference indicate corresponding parts in all the figures.

My invention has relation to gas-burning puddling-furnaces, and has for its object the introduction of heated air into the gas-chamber for the purpose of rendering the combustion of the gas more perfect; and it consists 25 in the improved construction and combination of parts of the same, as will be herein-after more fully described and claimed.

In the accompanying drawings, A represents the body of the furnace; B, the bottom 35 plates of the furnace; C, the false bottom of the same; D, the roof of the furnace; E, the neck of the same; F, the low gas-wall; G, the gas-burner, extending the full width of the furnace; H, the high gas-wall; I, gas-chamber; J, fire-bridge; K, flue-bridge; L, opening in flue; M, stack of furnace, and N the air-chamber. The above-mentioned parts are old, and form no part of my present invention.

O represents a partition-wall, which divides 45 the space between the false bottom C and the bottom of the furnace, and also the air-cham-

ber proper, N, into two spaces, A' A", the space A" being open at its outer end for the admission of cold air.

P indicates a flue which leads from the stack 50 of the furnace over the roof of the furnace and down into the hot-air space A', the flue P serving to bring hot products of combustion from the stack down into the hot-air space A'.

Q Q' indicate dampers which cover openings R R' in the rear end of the bottom plates 55 of the furnace, the damper Q regulating the amount of hot air fed through the hot-air flue A', while the damper Q' regulates the amount of cold air fed through the cold-air flue A".

From the foregoing description, taken in connection with the accompanying drawings, the construction and operation of my improved gas-burning puddling-furnace will readily be understood without requiring further explanation. It will be seen that by means of the dampers Q Q', I am enabled to regulate the amount of hot or cold air necessary for the proper combustion of the gas, thereby effecting a great saving of gas, and also rendering 65 the heat from the burners of an even quality and character.

Having thus described my invention, I claim and desire to secure by Letters Patent of the United States—

In a gas-burning puddling-furnace of substantially the described construction, the combination of the division-wall O, dividing the air-chamber into two flues or spaces, A' and A", flue P, leading from the stack of the furnace to the hot-air flue A', and dampers Q Q', regulating the amount of hot and cold air fed through the flues A' A" into the gas-chamber, as and for the purpose shown and set forth.

In testimony that I claim the foregoing as my 85 own I have hereunto affixed my signature in presence of two witnesses.

JOSEPH C. WILLIAMS.
